(57) **CLAIM**

We claim the ornamental design for a surgical light cover, as shown and described.

DESCRIPTION

FIG. 1 is a top right front perspective view of a surgical light cover showing our new design;

FIG. 2 is a bottom right front perspective view thereof;

FIG. 3 is a top plan view thereof;

FIG. 4 is a bottom plan view thereof;

FIG. 5 is a front elevation view thereof, the rear elevation view being identical to the front elevation view; and, FIG. 6 is a right side elevation view thereof, the left side elevation view being identical to the right side elevation view.

In FIG. 5, the broken lines illustrating a surgical light fixture are for illustrative purposes only and form no part of the claimed design.

The ornamental design for a flexible surgical light cover having adjustable straps for securing the light cover to a surgical light fixture.
